UNITED STATES PATENT OFFICE.

FRANCIS McMURDIE, OF KALAMAZOO, MICHIGAN.

BLAST-GATE.

1,384,204.

Specification of Letters Patent. Patented July 12, 1921.

Application filed April 6, 1920. Serial No. 371,659.

To all whom it may concern:

Be it known that I, FRANCIS McMURDIE, a citizen of the United States, residing at the city and county of Kalamazoo and State 5 of Michigan, have invented certain new and useful Improvements in Blast-Gates, of which the following is a specification.

This invention relates to improvements in blast gates.

10 The objects of the invention are to provide a simple and effective construction of blast gate which shall be securely packed against leakage and in which the slide will be frictionally held in any position desired.

15 Objects relating to details and economies of construction will definitely appear from the detailed description to follow.

I accomplish the objects of my invention by the devices and means described in the 20 following specification. The invention is clearly defined and pointed out in the claims.

A structure which is a preferred embodiment of my invention is fully illustrated in the accompanying drawing, forming a part 25 of this specification, in which:

Figure I is a detail sectional elevation taken on line 1—1 of Fig. II, of my improved blast gate in position.

Fig. II is a detail sectional view, some- 30 what enlarged, taken on line 2—2 of Fig. I, showing details of the support and the packing and support and adjusting means for the slide.

In the drawing the sectional views are 35 taken looking in the direction of the little arrows at the ends of the section lines and similar numerals of reference refer to similar parts throughout the several views.

Considering the numbered parts of the 40 drawing, 1 is a sheet metal pipe in which my improved blast gate is interposed. The blast gate support is made up of two oppositely disposed parts or plates 2, 2 provided with flanges 3 to which the pipe 1 is secured 45 by suitable screws 4 as illustrated. The two halves are secured together by a series of bolts 5 around the margin of the frame. Bosses 6, project beyond the faces of the plates so that the bolts clamp the same se- 50 curely together, leaving a space 7' for the passage of the slide 7. This passage and support extends down into projections 2', 2' below or at one side of the pipe, as the case

may be, forming an entrance throat for the reception of the gate. The slide is provided 55 with a handle 8 for manipulation.

On opposite sides of the gate within the entrance throat are supported packings 9 in suitable recesses 9', the same being fastened snugly against diametrically opposite sides 60 of the slide by bars 10, which are acted upon by set screws 11, so that any desired degree of pressure can be put upon the packing material and it can be forced air tight against the opposite sides of the slide and 65 being on diametrically opposite sides of the slide, it has little or no tendency to distort and warp the same. The set screws 11 for accomplishing this adjusting are provided with lock nuts 12 so that they may be se- 70 cured effectively in position.

I have described my improvements in the preferred form, but they may be considerably modified in detail without departing from my invention, which is defined and 75 pointed out in the appended claims.

Having thus described my invention, what I claim as new and desire to secure by Letters Patent, is:

1. In a blast gate structure, the combination 80 of symmetrically opposed halves, suitably spaced from each other to form a guide and support for the slide and fitted tight at their peripheries and extended to form an entrance throat, packing material in suitable 85 recesses on diametrically opposite sides of the slide within the entrance throat, bars for urging the said packing material against the diametrically opposite sides of said slide, and suitable screws for applying pressure 90 thereto, coacting as described for the purpose specified.

2. In a blast gate structure, a frame with 95 guide for the slide with entrance throat therefor, packing means for said slide comprising diametrically opposed recesses within said throat, packing material in the recesses, and bars back of the material with means of compressing the same, as specified.

In witness whereof, I have hereunto set 100 my hand and seal in the presence of two witnesses.

FRANCIS McMURDIE. [L. s.]
